[57] CLAIM

The ornamental design for a wing nut, as shown and
described.

DESCRIPTION

FIG. 1 is a perspective view of a wing nut, showing our new
design;

FIG. 2 is a front elevational view thereof;

FIG. 3 is a right side elevational view thereof, the left side
elevational view being identical;

FIG. 4 is a top plan view thereof; and,

FIG. 5 is a bottom plan view thereof.
